UNITED STATES PATENT OFFICE.

FRANCIS LEE STUART, OF WASHINGTON, DISTRICT OF COLUMBIA, ASSIGNOR TO
INTERNATIONAL CONVEYOR CORPORATION, OF NEW YORK, N. Y.

STORING AND RECLAIMING APPARATUS.

1,275,319.

Specification of Letters Patent. Patented Aug. 13, 1918.

Application filed December 22, 1917. Serial No. 208,355.

To all whom it may concern:

Be it known that I, FRANCIS LEE STUART, a citizen of the United States, and a resident of the city of Washington, District of Columbia, have invented certain new and useful Improvements in Storing and Reclaiming Apparatus, of which the following is a specification.

This invention relates broadly to a storing and reclaiming apparatus, and more particularly to an apparatus of this type for receiving materials from a main source of supply, conveying the same to storage, and then reclaiming and reloading the same.

The principal object of the present invention is to provide an apparatus constructed of a plurality of units which may be readily brought into position and assembled for use.

A further object of the present invention is to provide each unit conveyer with means for driving the same, and also with means for moving the unit from place to place for use as desired.

A further object of the present invention is to provide a transfer table adapted to receive the material to be handled from a main conveying means, and coöperating with the unit conveyers whereby the material may be readily transferred thereto.

Still another object of the present invention is to provide a stacker or trimmer which is complete and portable from place to place to coöperate with any desired source of supply.

A still further object of the present invention is to provide a system employing the various apparatuses before referred to whereby material may be quickly and easily received from a main source of supply, such as a track hopper, and conveyed to storage devices from which it may be reclaimed and reloaded at will.

The foregoing and other objects, together with their attendant advantages, will be apparent from the accompanying specification, and drawings forming a part thereof, throughout the several views of which like characters of reference have been used to indicate like parts. In the drawings, which are largely diagrammatic, Figure 1 is a perspective view of my improved apparatus showing the same in position for receiving material from a track hopper, and deliver-

ing the same to a suitable stacker and forming storage piles from which the material is subsequently reclaimed.

Fig. 2 is a plan view of the apparatus shown in Fig. 1.

Fig. 3 is a diagrammatic elevation looking in the direction of the arrow *a* from the line A—B of Fig. 2.

Fig. 4 is an enlarged detail view of a unit conveyer.

Fig. 5 is an end view of a transfer table employing a shuttle conveyer delivering in either direction to unit sectional conveyers on either side of a transfer pit.

Fig. 6 is an end view of the transfer table carrying a reclamer and a plurality of sectional unit conveyers.

Fig. 7 is an enlarged view of the discharging end of a reclaiming apparatus in coöperative relation to a sectional unit conveyer.

Fig. 8 is a modified form of the apparatus illustrated in Fig. 5.

Fig. 9 is a view similar to Fig. 6 showing a stacker in place of the reclamer.

Fig. 10 is a plan view of a self-contained stacking device.

Fig. 11 is a side view of the construction shown in Fig. 10.

Fig. 12 is a plan view of a track hopper and associated mechanism.

Fig. 13 is an elevation of the construction illustrated in Fig. 12.

In handling material in bulk, such as coal, ore, and the like, it is necessary in order to expedite the loading of the same that both a main and secondary source of supply be provided. In systems with two sources of supply, it is customary to replenish the secondary source of supply from the main source, and then subsequently reclaim and reload from the secondary source. Belt conveyers, commonly employed for this purpose, frequently have a length of several hundred feet, so that the cost of installation and upkeep is an item of considerable importance. Furthermore, where continuous belt conveyers are employed it is necessary to provide troughing and supporting rollers for the upper and lower run of the belt, respectively, so that the entire conveyer when once installed is more or less fixed. It is the object of this present invention to provide sectional or unit conveyers which

70

75

85

95

100

105

may be kept on hand in any desired number and coupled together for use as desired, so that the necessity of employing permanently located belts is obviated. By reason of this construction, both the cost of installation and the cost of upkeep of the system are reduced.

Referring more particularly to the drawings, I have illustrated a main source of supply as comprising cars C delivering to 10 track hoppers H, as shown more particularly in Fig. 13, having outlets 1 discharging onto the inclined conveyers 2, each driven by a suitable source of power 4, for supplying the receiving hopper 5 feeding the main conveying means, here shown as a belt conveyer 6. The track hoppers and associated mechanism may be placed, as is customary in this art, in pits 7 whereby the cars C are easily moved to discharging position over 20 the same.

For storing the material received from the track hoppers, the main conveyer 6 has a looped portion 8 passing around the tripper 9 adjustable on the track 10 by means 25 of a motor or the like 11. The tripper may be of the type disclosed in my Patent No. 1,207,237, of December 5, 1916. The frame work of the tripper is connected at 12 to a transfer table T on the tracks 10 and adjustable with the tripper. If desired, the transfer table may also be provided with a source of power 14 so that the same may be independently moved to the desired position. The upper end of the tripper 9 discharges 30 into a hopper 15 having oppositely extending outlets 16 for delivering material to the shuttle conveyer 17 mounted in the frame 18 and having suitable driving mechanism 19. The shuttle conveyer is adjustable 35 on the frame 20 of the transfer table by means of the motor 21, and is provided with discharges 22 adapted to be brought into operation in accordance with the direction of travel of the shuttle conveyer. The discharges 22 are disposed in coöperative relation to the upper run of the unit conveyer belts 24 mounted on the frames 25 which are self-movable by the driving mechanism 26. An operating means 27 for the unit 40 conveyers makes the same self-contained so that each unit may be used independently of any other unit, or may be used in conjunction therewith. The unit conveyers preferably have their ends 28 inclined and 45 provided with hoppers 29 whereby an independent unit conveyer may be moved to coöperating position therewith. The entire transfer table T is preferably disposed in a pit 30 so that the upper surface of the transfer table is flush with the surface of the adjoining ground. By reason of this construction the unit conveyers 24 may be readily moved onto the transfer table and projected therefrom so as to receive material from the 50 discharges 22. The transfer table may be

constructed so that any number of unit conveyers may be simultaneously carried thereon.

The unit conveyers as they receive material from the shuttle conveyer 17 discharge 70 the same onto the tripper 31, constructed in a manner similar to the tripper 9 and discharging to the stacker S forming storage piles, or secondary sources of supply P.

From the foregoing description, it will be 75 obvious that by reason of the unit conveyer construction, the position of the stacker S may be controlled at will so as to deposit material adjacent the main conveyer 6 when only a single unit is employed, or at a considerable distance therefrom when a plurality of units are utilized. As clearly shown in Figs. 1 and 2 the unit conveyers 24 may be positioned and kept on sidings 32 from which they may be easily run onto the transfer table T and moved to a position in which they will coöperate with the main conveyer. By employing a shuttle conveyer, the material supplied by the main conveyer may be delivered to a unit conveyer not located on the transfer table as indicated in Fig. 4 even though the transfer table carries a spare unit conveyer. In some cases, however, I may dispense with the shuttle conveyer and provide a simplified transfer table construction such as shown more particularly in Figs. 8 and 9 of the drawings. Referring to these figures, it will be seen that the tripper 9' discharging to the hopper 15' supplies material directly to the unit conveyer 24 90 through the outlet 16'. Such a construction while doing away with the shuttle conveyer, may be successfully used by so placing the unit conveyers 24 that the joints therebetween do not come directly under the outlet 105 16', although in actual practice the conveyers in assembled relation occupy such positions that comparatively little space exists therebetween.

In still other cases it is desirable to employ a stacker S', fully illustrated in Figs. 10 and 11, which is self-contained and movable as a unit from place to place. This stacker comprises a framework 34 traveling on the wheels 35 and carrying a conveyer 110 belt 36 driven by the motor 37. The main difference between this construction, and that disclosed in Fig. 6 resides in the employment of a conveyer 36 which is independent of any other conveyer belt, but 115 120 which is adapted to coöperate therewith for receiving materials. For example, a unit conveyer 24 may supply material thereto through the hopper 29 positioned adjacent the lower end of the frame 34. At its upper 125 end, the conveyer 36 discharges through a hopper 38 and outlet 39 to the stacker S' pivotally supported on the trunnions 40 carried by the rotatable or turntable construction 41 carried by the truck 42. The truck 130

42, as is the case with the other trucks employed throughout my apparatus is preferably driven by a motor 44 so that the stacker may be moved to storing position. Angular 5 adjustment of the stacker is obtained by the motor 45 driving the pinion 46 coöperating with a segmental rack gear 47. Due to the turntable support for the stacker it is easily swung or adjusted laterally, as indicated in 10 dotted lines in Fig. 10. The self-contained construction rendering the entire stacker and tripper easily portable is highly advantageous in that the necessity of employing a separate tripper and stacker for each belt is 15 overcome.

After the material has been stored in piles or warehouses P, it may be readily reclaimed by employing a reclamer R, which may be constructed in accordance with any of the 20 forms disclosed in my copending application, Serial No. 201,798 filed Nov. 13, 1917. As herein shown, the reclamer comprises a reclaiming digger 48 elevating material to the boom conveyer 49 having one end supported in coöperative relation with the hopper 50 mounted on the adjustable truck 51. The truck 51 is preferably mounted to discharge to a unit conveyer 24 of the type described delivering through the connecting 25 30 hopper 29 to a stacker or loading trimmer S' adapted to deliver either to the cars C' or to the conveyer 52, which may in turn load either the barges B or the vessel V through the trimmer 54, which may be constructed as 35 disclosed either in my Patent No. 1,207,237, of December 5, 1916, or No. 1,231,449, of June 26, 1917. In Fig. 7, the discharging end of the reclaiming conveyer is shown in detail, together with the motor 55 for driving 40 the same, and the motor 56 for producing longitudinal adjustment of the truck 51 through the driving belt 57 and its associated mechanism.

In some cases I may employ a modified 45 mounting for the reclamer 49. Such a modification is illustrated in Fig. 6 in which the truck 51 is illustrated as being carried by the transfer table T in coöperative relation with one of the unit conveyers 24. Such 50 a construction permits the rapid positioning of a unit conveyer by reason of the pit construction 30.

In like manner, the stacker S' may be mounted on the transfer table, as shown dia- 55 grammatically in Fig. 9.

By employing self-contained unit conveyers, and self-contained trimmers and stackers which may be easily moved from one point to another, an expeditious and 60 economical handling of material is effected. Any means may be employed, if desired, for interconnecting the unit conveyers, although such a construction is not necessary, by reason of the fact that each conveyer may be 65 independently moved to its final position.

Since many changes may be made in the structural embodiment of the various pieces of apparatus employed, it is intended that the drawings shall be considered as illustrative of preferred forms, rather than in a 70 limiting sense.

In my application for patent filed March 19, 1918, No. 223,302, I have shown and claimed the construction of the stacker hereinbefore described and in said application I 75 have also claimed a system comprising a stacker such as shown in the accompanying drawings and unit conveyers of the kind hereinbefore shown and described, said unit conveyers being arranged end to end, de- 80 livering one to the other and in turn delivering to the stacker, said unit conveyers being arranged on a track disposed transversely to the main conveyer which is provided with a tripper delivering to the unit conveyers. I 85 do not therefore herein claim said subject matter.

In my application for Patent No. 233,514, filed May 4, 1918, I have shown, described and claimed certain improvements in unit 90 conveyers of the general kind shown in the accompanying drawings and I do not herein claim the particular construction of unit conveyer hereinbefore described.

Having thus described my invention, what 95 I claim is:—

1. A system for storing material, comprising truck-supported unit conveyers, a track on which they are stored, a truck-supported transfer table provided with means for receiving and supporting the unit conveyers, a conveyer belt which receives material to be stored, a tripper coöperating with said belt and movable with the transfer table, means for conveying the material from the tripper 100 to a unit conveyer, and means for delivering material from the unit conveyer. 105

2. A system for storing material, comprising truck-supported unit conveyers, a track on which they are stored, a truck-supported 110 transfer table provided with means for receiving and supporting the unit conveyers, a conveyer belt which receives material to be stored, a tripper coöperating with said belt and movable with the transfer table, means 115 for conveying the material from the tripper to a unit conveyer carried by the transfer table, and means for delivering material from the unit conveyer.

3. A system for storing material, comprising truck-supported unit conveyers, a track on which they are stored, a truck-supported transfer table provided with means for receiving and supporting the unit conveyers, a conveyer belt which receives material to be stored, a truck-supported tripper 120 connected to and movable with the transfer table and coöperating with said belt conveyer, means for conveying material from the tripper to a unit conveyer, and means 125 130

for discharging material from the unit conveyer.

4. A system for storing material, comprising truck-supported unit conveyers, a track on which they are stored, a truck-supported transfer table provided with means for receiving and supporting the unit conveyers, a conveyer belt which receives material to be stored, a truck-supported tripper connected to and movable with the transfer table, and coöperating with said belt conveyer, means for conveying the material from the tripper to a unit conveyer carried by the transfer table, and means for discharging material from the unit conveyer.

5. A system for storing material, comprising truck-supported unit conveyers, a track on which they are stored, a truck-supported transfer table provided with means for receiving and supporting the unit conveyers, a conveyer belt which receives material to be stored, a tripper coöperating with said belt and movable with the transfer table, a shuttle conveyer on the transfer table receiving material from the tripper and delivering to a unit conveyer, and means for discharging from the unit conveyer.

6. A system for storing material, comprising truck-supported unit conveyers, a track on which they are stored, a truck-supported transfer table provided with means for receiving and delivering to the unit conveyers, a conveyer belt which receives material to be stored, a tripper coöperating with said belt and movable with the transfer table, a shuttle conveyer on the transfer table receiving material from the tripper and delivering to a unit conveyer carried by the transfer table, and means for discharging from the unit conveyer.

7. A truck-supported transfer table provided with a shuttle conveyer and means below the shuttle conveyer for supporting a unit conveyer.

8. A transfer table provided on its upper portion with an extensible or shuttle conveyer, a track below the shuttle conveyer for supporting a unit conveyer, and another track on the transfer table for supporting a reclaimer or a stacker.

In testimony whereof I have hereunto subscribed my name.

FRANCIS LEE STUART.
